UNITED STATES PATENT OFFICE.

JAKE ZYLSTRA, OF SHELDON, IOWA.

HUSKING DEVICE.

Application filed September 27, 1926. Serial No. 137,968.

My present invention has reference to a snapping and husking roll for corn husking machines, and my object is the provision of a roll for this purpose which will effectively 5 grab the husk to remove the same from the ear of corn.

A further object is the provision of a roll for this purpose in which a shaft extends through and is fixed to a wooden body or 10 core, the latter, from its forward end and for the major portion of its length, being hexagonal in cross section, the remainder of its length being round in cross section and the core being provided with a comparatively 15 thick facing of abrasive material, such as emery, the rollers designed to grip the husk between the corners thereof, and the round portion of the rollers removing the inner or last portion of the husk from the corn ear, 20 the facing being of great strength and hardness so that the same will not easily wear and will always retain a rough surface.

The drawings illustrate a satisfactory embodiment of the improvement, and wherein:

25 Figure 1 is a plan view of snapping and husking rolls in accordance with this invention.

Figure 2 is a longitudinal sectional view through one of the rolls.

30 Figure 3 is a transverse sectional view on the line 3—3 of Figure 1.

Figure 4 is a similar sectional view on the line 4—4 of Figure 1.

In the showing of Figure 1 of the drawings one of the rolls 1 is of a greater length than the second and cooperating roll 2. Both rolls are provided with the usual shafts that have meshing gears 3. The shafts extend through hard wood members which I will 35 term cores 4. The cores are preferably of oak and have their outer faces, for the major portion of their length of hexagonal cross section, as indicated by the numeral 5. The inner portions of the cores are round in cross 40 section, as indicated by the numeral 6. The outer end of each core is tapered, as at 7. The cores 4 have fixedly secured thereon an outer facing 8 of emery or like abrasive material. The facings 8 are comparatively 45 thick, the thickness of the same being approximately one-half of an inch and the facings are of great hardness as well as strength

and always maintain an outer roughened surface.

Approximately the round portions of the 55 rolls are 12 inches, the hexagonal portion of the longer roll 3 ft., 3 $\frac{1}{4}$ inches, and the hexagonal portion of the shorter roll 2 ft., 11 $\frac{1}{2}$ inches. The corn delivered between the flared ends of the roll may be engaged by the 60 corners of the hexagonal portions thereof so that the husks will be effectively gripped and removed from the ears of corn without injury to the latter. Any husks that may remain on the ears may be removed by the cross 65 sectionally rounded portions of the rolls. The rolls will not clog or get overloaded, as they present a roughened surface throughout the length thereof, and by virtue of such 70 roughened surface the husks will at all times be effectively gripped and removed from the ears of corn. The cross sectional diameter of the rolls is approximately 4 inches.

Having described the invention, I claim:

1. A snapping and husking roll for the 75 purpose set forth comprising a core of hard wood having a shaft extending centrally therethrough and secured thereon, said core having a comparatively short inner portion which is round in cross section and a longer outer portion which is hexagonal in cross 80 section, and a comparatively thick facing of abrasive material for the core.

2. Snapping and husking rolls for corn 85 husking machines, each comprising a hard wood core having a shaft extending centrally therethrough and fixed thereto, one of said cores being of a greater length than the other and the inner ends of each core having comparatively short cross sectionally rounded 90 portions of the same length, the remaining portions of the cores being hexagonal in cross section and the outer ends of the said portions being tapered, and a comparatively 95 thick emery facing for each of the cores.

3. Snapping and husking rolls having cylindrical adjacent portions at one end thereof and portions toward the other end thereof 100 polygonal in cross section and having converging sloping surfaces, one of said rolls being of greater length than the other.

In testimony whereof I affix my signature.

JAKE ZYLSTRA.
